SANDER HEAD

George W. Bruner, Indianapolis, Ind., assignor,
by mesne assignments, to Anton Vonnegut,
Indianapolis, Ind.

Application May 26, 1951, Serial No. 223,453

5 Claims. (Cl. 51—191)

1

This invention relates to a sander head, particularly of the expanding self-adjusting type wherein there is provided a plurality of radially movable segments acting under centrifugal force to tighten against the abrasive belt and permit of a cushioning effect when engaging with the work.

In sander heads of this type it has been customary to provide a circular abrasive belt passing directly around the head with which the segments engage. Upon rotation of the head, centrifugal force causes the segments to firmly engage the belt in their expanded position so that there will be no slippage therebetween. With the circular belt structure the abrasive becomes worn, overheated and destroyed in a short time, requiring replacement at frequent intervals.

It is the purpose of this invention to provide a structure of the above character, but wherein the overall length of the abrasive belt may be greatly increased to provide a substantially greater length of abrasive surface and thereby increase the life of the belt. By this arrangement both the life and usefulness of the belt may be increased, and where desired the diameter of the head may be decreased for permitting application thereof to interior surfaces.

A feature of the invention resides in the structure of the head in association with an internally-looped belt so arranged with respect to the radially movable segments as to increase the length of the belt and cause a creeping action of the belt over the respective segments during use. Such creeping action continuously feeds the belt over the segments in such manner as to present fresh relatively cool abrasive surfaces about the head as the exposed and heated surfaces become worn.

Other features and advantages of the invention will become more readily apparent from the following specifications and the attached drawings.

The full nature of the invention will be understood from the accompanying drawings and the following description and claims:

Fig. 1 is a side elevation of one form of abrasive head with a portion broken away and the upper half thereof shown in central vertical section.

Fig. 2 is a section taken on the line 2—2 of Fig. 1.

Fig. 3 is a side elevation showing a modified form of head with the upper portion thereof shown in central vertical section.

Fig. 4 is a section taken on the line 4—4 of Fig. 3.

In the drawings there is shown a sander head as illustrative of one modification of the inven-

tion, which head comprises a pair of annular opposed side plates 10 and 11 secured to the hub 12. Said hub is provided on one end thereof with a retaining and driving flange 13 secured to the plate 10 by the screws 14. Mounted adjacent the periphery of the plates 10 and 11 and extending therebetween there is an annular series of spaced pairs of guide pins 15 and 16 arranged in annularly spaced relation about the periphery of said plates. The pins of each pair are in radially spaced alignment with each other. Said pins are rigidly and permanently secured at one end to the plate 10 and are provided with reduced ends adapted to be received in suitable bearing recesses provided in the plate 11.

Slidably carried by each pair of said pins 15 and 16 there is an applicator pad 17 forming a segment of the head. Each of said segments may preferably comprise a metal base plate 18 carrying a looped strap 19 extending inwardly therefrom and embracing a pair of pins 15, 16. The looped strap is elongated to extend radially inwardly and of greater overall length than the overall distance between the pins so as to freely slide thereon from a normally restricted position, as shown in Fig. 1, to an extended position under the influence of centrifugal force upon rotation of the head.

Also engaged and secured between the two side plates adjacent the hub 12 there is an annular series of circumferentially spaced bearing pins located radially inwardly from the space between the respective applicator pads. Said bearing pins mount a cylindrical roller 21 for free rotation thereabout. Each of the bearing pins has one end thereof rigidly secured to the plate 10, the other end being slidably receivable in a recess provided in the plate 11. The plate 11 is movable from the guide pins and bearing pins to permit of convenient mounting of the applicator pad segments 17, and the abrasive belt to be herein-after described. Such plate 11 is locked in place by a suitable lock nut 22 threaded on the adjacent reduced end of the hub 12.

The abrasive belt 23 is of the endless type but instead of passing directly about the periphery of the head, it is threaded inwardly between adjacent applicator pad segments toward the hub for passing about the rollers 21. Thus, the belt is greatly increased in length over that of that of the usual type by causing it to alternately pass inwardly and outwardly about the rollers 21 and the adjacent applicator pads 17, respectively.

Whereas the immediate application of the wheel to the work presents only the exposed por-

tion of the belt extending over the exterior of the applicator pads, said belt will be caused to creep thereabout and thereby slowly but continuously present fresh, unused abrasive surfaces. This is brought about by the reciprocable action of the applicator pad segments on their guide pins resulting from the intermittent action of centrifugal force when free of the work and retraction when engaging the work. Such reciprocation periodically loosens the belt relative to the surface of the pad upon contact with the work, permitting it to slip relative to the surface of the pad under the influence of friction between the applied portion of the belt and the surface of the work. This is followed by a tightening of the engagement or contact between the pad and the belt as it leaves the work following the slight frictional displacement. This action becomes progressive as the respective pads come into engagement with and leave the work, resulting in the automatic feeding of the elongated belt to constantly bring an unused portion thereof into work engaging position.

In the modified form shown in Figs. 3 and 4 the above arrangement is varied to permit of its use in a head of substantially less diameter. In this form the side plate 110 is welded to the hub 112 and a reinforcing outer disk 113, the guide pins 15 and 16 being rigidly secured within the side plate 110. The side plate 111 is removably mounted relative to said pins, being secured on the radius of the hub 112, by the threaded nut 122. Each bearing pin 20 carrying its roller 21 is secured to the side plate 110 and removably supported at its opposite end by the plate 111. The applicator pad segments 17 are each similarly provided with a looped guide strap 19 embracing and slidably mounted upon the guide pins 15 and 16. The abrasive belt 23 alternately passes inwardly about the rollers 21 and outwardly about the adjacent applicator pad segments 17.

This modified form is in all respects the same as above described and functions in the same manner to bring about the same results, other than to encompass the structure in a head of minimum diameter, the rollers 21 are offset to one side of their respective adjacent applicator pad segments so that the loop of the belt extending thereabout is directed at a substantial angle to the radius.

From the foregoing it will be observed that such a head having spaced radially slidable applicator pad segments with the abrasive belt looped inwardly therebetween to adjacent the hub will provide a more efficient sander head of longer life due to the substantially increased length of the belt and the creeping or feeding action to present a fresh unused surface thereof during its application to the work.

The invention claimed is:

1. A sander head comprising a hub and spaced side supports, an annular series of applicator segments mounted in spaced relation about the periphery of said supports for individual and restricted radial sliding movement, a corresponding annular series of rollers carried by said supports inwardly of said segments toward said hub, and an endless abrasive belt passing alternately about corresponding rollers and segments respectively movable thereover to present an annular series of individual separated abrasive surfaces.

2. A sander head comprising a hub and spaced side supports, an annular series of applicator

segments defining the periphery of said head, bearing members secured between said side supports slidably mounting said segments thereon for individual limited radial movement, a corresponding annular series of rollers carried by said supports inwardly of said segments towards said hub, and an endless abrasive belt passing alternately about corresponding rollers and segments respectively movable thereover to present an annular series of individual separated abrasive surfaces.

3. A sander head adapted to be applied to a work surface, comprising a hub, a radially extending frame mounted on said hub, an annular series of applicator segments defining the periphery of said head, means for supporting said segments within said frame for limited radial movement relative thereto and to each other, a corresponding annular series of rollers carried within said frame inwardly of said segments towards said hub, and an endless abrasive belt passing alternately about said corresponding rollers and segments respectively movable thereover under the influence of periodic radial movement of said segments and frictional force during application to the work surface.

4. A sander head adapted to be applied to a work surface, comprising a hub, a radially extending frame mounted on said hub, an annular series of applicator segments defining the periphery of said head, means for supporting said segments in peripherally spaced relation within said frame for limited radial movement relative thereto and to each other, a corresponding annular series of anchor members carried within said frame inwardly of said segments toward said hub, and an endless abrasive belt passing alternately about said corresponding anchor members and segments respectively to present an annular series of individually separated abrasive surfaces.

5. A sander head adapted to be applied to a work surface, comprising a hub, a radially extending frame mounted on said hub, an annular series of applicator segments defining the periphery of said head, means for individually and independently supporting said segments in spaced relation within said frame for limited radial movement relative thereto and to each other, a corresponding annular series of anchor members carried within said frame inwardly of said segments toward said hub, each of said anchor members being angularly displaced in offset relation to a radial plane extending between the spaced segments, and an endless abrasive belt passing alternately about said corresponding anchor members and segments respectively to provide an inner looped portion directed at a substantial angle to said radial plane.
